Laboratories, New York, N. Y., a corporation of
New York

Application June 2, 1938, Serial No. 211,378

11 Claims. (Cl. 240—78)

The present invention relates to luminaires, and is more particularly directed toward dual purpose luminaires for dining-room lighting.

When in a private home a dining-room is utilized for dining purposes it may not be generally appreciated, but it is a fact, that the dining table dressed with cutlery, china and silverware, is most attractive and interesting if polished surfaces of such equipment glitter and sparkle. This appearance cannot be had if the light is soft and diffused. It is achieved to some extent when the principal light is derived from candles on the table. These little points of flickering light of the candle flame are reflected in the polished surfaces as points of brightness lending interest and charm to the table scene. But the effect is achieved only in a small degree because of the low brilliancy and low illuminating power of candles. In order to achieve it in a greater degree, it is necessary to deliver upon the table harsh brilliant light which would be entirely unsuitable for a work surface or in any place where the source of light is exposed to the eyes. Such an effect can best be obtained by permitting light from an incandescent lamp filament, without any softening or diffusion, to fall upon the table surface.

A second requirement for lighting of a dining-room for dining purposes is that the light upon the faces of the diners should be soft, directed somewhat from above and of a becoming tint. This, to a degree, is accomplished by the use of candles. The light from the candle flame is of a generally pleasing tint. Unless the candlesticks or candles be very tall, the light sources are rather too low for best effect and the amount of light available from candles is inadequate. Candlelight, however, is highly appreciated by many because in spite of its deficiencies of natural placement and low illuminating value, it is considered to be a becoming light. The desired effect upon the faces of diners partially obtained by the use of candles may be attained in full measure by employing light from a luminaire suspended over the table to illuminate a zone around the table in which the diners are seated and by insuring that the light in this peripheral zone shall be soft and pleasingly tinted. It would be marred if the harsh, brilliant light needed for brilliance in lighting table equipment were to be allowed to fall on the faces of the diners. It should therefore be of an entirely different quality from the "raw light" falling upon the table and the demarcation between the zone of "raw light" for table illumination and the zone

of softly tinted light for face illumination should be adjustable to conform to different sizes of tables and different heights of mounting of a luminaire. Furthermore, there is always a question as to which is the most satisfactory tint for the light to be employed for illumination of the faces of diners. This may vary depending upon the decorations of the room, and the decorations of the table. It may also vary with special occasions (as Hallowe'en, Christmas, etc.). From this there arises the desirability of easily changing the tint of the light employed to illuminate faces of diners.

A third requirement for effective lighting of dining-rooms for dining purposes is that the principal lighting and therefore the principal point of attention in the room should be the table and the diners. The remainder of the room should be softly but not conspicuously illuminated.

When the service of dinner is complete, it often occurs that the room is put to other use, as, for example, for home study of children, for playing of games, etc. For such purposes, lighting of an entirely different character is required. That provided for dining would be unsuitable. Here general lighting of ample intensity and diffused for the avoidance of glare is the requirement. Hence the desirability of equipping dining rooms with luminaires which can be employed alternately for dining purposes or for general purposes.

The present invention contemplates a luminaire designed for the above purposes, and in carrying out the design, the luminaire has been designed to facilitate relamping, change of color value of the diffused peripheral light and of angle subtended by the central zone of harsh direct light.

The accompanying drawing shows, for purposes of illustrating the present invention, an embodiment in which the invention may take form, it being understood that the drawing is illustrative of the invention rather than limiting the same.

In the drawing:

Figure 1 is a diagrammatic view illustrating the relations of the luminaire, the table and the zones of light;

Figure 2 is a vertical sectional view through the luminaire;

Figure 3 is an enlarged vertical sectional view showing a detail of construction;

Figure 4 is a view taken on the line 4—4 of Figure 3; and

Figure 5 illustrates a modification.

The fixture is supported on a stem, indicated at 10, through which the wires pass. This stem supports a hickey 11 in which is threaded a nipple 12. A piece of tubing 13 is received in the nipple 12 and is clamped in place by a screw indicated at 14. The tubing 13 supports a pendent lamp socket 15 which carries a lamp bulb 16 and a reflector 16'. This lamp bulb is preferably a clear glass bulb with a naked filament indicated at 17.

The nipple 12 also supports a spider, indicated at 18, which carries a cluster of lamp sockets 19 for lamps 19' and the chains, indicated at 20, for supporting a bowl 21. This bowl may be made of dense pressed glass or plastic material so that the reflected light is greater than the transmitted light, and may be of any suitable profile. The bowl 21 has a central hole 22 somewhat larger in diameter than the lamp bulb 16. Where the bowl is made of glass or of other easily frangible material the opening 22 is provided with protective rings 23 and 24 held together by screws 25 which pass through the flattened portions of the rings. These flattened portions have aligned openings, indicated at 26 and 27, and a short distance from the aligned opening the upper ring 24 is provided with a notch indicated at 28.

The closure for the opening in the bowl 21 is preferably in the form of a piece of transparent material having a profile to continue the profile of the bowl as indicated at 29. It is provided with a peripheral ring 30 and clips 31. The ring 30 is provided with projecting tongues 32 adapted to pass up through the openings 26 and 27 and be turned slightly so as to enter the recesses or notches 28 after the fashion of a bayonet joint.

The metal ring 30 supports a tubular light transmitting collar 33 which extends up between the bulb 16 and the bulbs 19'. This collar may be made either of transparent or of translucent material and is designed to tint the light transmitted through it. A suitable form of collar 45 may be made out of tinted glass with or without an opal flashing, indicated at 34. If the tubular collar is made slightly diffusing in character by the application of a thin flashing, enameling or frosting, the outer lamps 19' may thus be prevented from casting sharp shadows on the bowl when the central lamp 16 only is lighted. If such shadows are unobjectionable, as, for example, if they are more or less concealed by decoration on the outer surface of the bowl, then the 50 tubular collar may be transparent. The collar 33 is generally cylindrical, but where the area to be lighted is square or rectangular the shape of the clear aperture at the bottom of the collar may be altered by the insertion in the bottom of 55 the collar of a disc having a transparent central aperture of the desired shape, the outer area of the disc having a diffusing character and being tinted if and as desired.

The luminaire is intended for mounting over a dining-room table T, as shown in Figure 1. The harsh undiffused direct light from the filament 17 passes down through the transparent member 29, as indicated by rays 35, providing a zone of direct light which is intended to coincide with 60 the top of the table for the purpose of lighting up the objects on the table. The angle of this zone of direct light may be controlled by changing the mounting height of the socket 15 when the screw 14 is loosened. The light which is 65 transmitted through the tubular collar 33 falls

on various areas of the outer light diffusing bowl 21 for transmission downwardly and for reflection upwardly. The downwardly and outwardly transmitted light which passes through the collar 33 and the bowl 21 gives a zone of diffused and tinted light which falls on the faces of the persons seated at the table and provides a soft pleasing general illumination reinforced by some indirect light coming from the ceiling. Between the zone of harsh direct light and the zone of diffused and tinted light there is a narrow or transition zone of mixed light as indicated in Figure 1. The shape of the zone of downwardly directed undiffused light may be altered by inserting in the bottom of the collar a disk 40 having a transparent central aperture of the desired shape and an outer diffusing portion as indicated in Figure 5.

When the central pendent lamp is extinguished and the upper lamps carried in the sockets 19 are lighted, the fixture becomes a semi-direct lighting fixture providing light for general purposes.

A small three-light switch 37 is incorporated in the luminaire for convenience in lighting the central lamp 16 alone, the outer lamps 19' alone or all lamps at once as desired. The switch may be made inconspicuous by placing it at the point of attachment of one of the suspension chains to the bowl as shown in the drawing.

It will be noted that the construction shown is one which permits ease of adjustment of the height of the central bulb and also ease of removal of the bottom closure member 29 and ring 33 for cleaning, for relamping or for substitution of variously tinted collars.

In the drawing the covers for the upper lamp sockets and the hickey are omitted for clearness.

It is obvious that the invention may be embodied in other forms and constructions within the scope of the claims. Various modifications and changes being possible, we do not otherwise limit ourselves in any way with respect thereto.

What is claimed is:

1. A luminaire for lighting a table or the like, comprising a dish-shaped translucent light reflector, disposed over the table and having at the bottom a centrally disposed, substantially transparent optical window; an axially disposed clear glass lamp, mounted to have its filament disposed a substantial distance above the window so that light issuing from this lamp within a determinable zone from nadir may pass without modification through the window for lighting the table; and a readily replaceable colored collar extending upward from the periphery of the window to be above the light source of the lamp and intercept all light directed toward the walls of the reflector so as to tint the light from the lamp which falls upon the surface of the reflector, such light providing an outer zone of diffused general illumination of any desired hue.

2. A luminaire such as claimed in claim 1, wherein the window includes a transparent closure which is downwardly removable to afford access to the lamp.

3. A luminaire such as claimed in claim 1, wherein the window includes a transparent closure which is downwardly removable to afford access to the lamp and the tubular collar is downwardly removable to facilitate substituting one of different light transmitting property whereby the character of the outer zone of light may be altered.

4. A luminaire such as claimed in claim 1,

having means for mounting the lamp at varying relative heights whereby the angle of the zone of undiffused light may be varied.

5. A luminaire such as claimed in claim 1, 5 having a reflector inside the tubular collar and above the lamp for intercepting upwardly directed direct light and reflecting it down through the window.

6. A luminaire such as claimed in claim 1, 10 wherein the shape of the zone of downwardly directed undiffused light may be altered by the insertion in the bottom of the central collar of a disc having a transparent central aperture of the desired shape, the outer portion of the disc 15 having a diffusing character.

7. A luminaire having a pendent lamp with a clear glass bulb, a colored tubular collar about the lamp and extending a substantial distance below and above the filament of the lamp, a 20 transparent optical window at the bottom of the tubular collar for transmitting a beam of direct undiffused light, and an outwardly flaring light reflector-diffuser extending upwardly from the bottom of the tubular collar for transmitting 25 downwardly and outwardly a portion of the colored light received through the tubular collar and for upwardly reflecting a portion of the said light received through the tubular collar for indirect lighting.

30 8. A luminaire such as claimed in claim 7, having a downwardly acting reflector received in the upper part of the tubular collar.

9. A luminaire such as claimed in claim 7, 5 having supplemental lamp bulbs disposed between the tubular collar and the flaring reflector-diffuser for increasing both the diffused direct and the indirect components of light.

10. A luminaire having a support, a pendent lamp socket, a lamp bulb therein, an upwardly opening light diffusing bowl carried by the support, the bowl having a central opening below the pendent lamp bulb, a transparent closure 10 member for the opening, means for detachably securing the closure member in place, and a downwardly removable, colored light transmitting collar of smaller diameter than the opening 15 carried by the securing means and extending above the filament of the lamp bulb.

11. A luminaire having a support, a pendent lamp socket, a lamp bulb therein, an upwardly opening light diffusing bowl carried by the support, the bowl having a central opening below 20 the pendent lamp bulb, a transparent closure member for the opening, means for detachably securing the closure member in place, a translucent ring of smaller diameter than the opening 25 and supported from the securing means to be about the lamp bulb, and a plurality of lamp bulbs carried by the support and extending into the space between the ring and the bowl.
